UNITED STATES PATENT OFFICE.

MALCOLM L. COSSITT, OF ALAMEDA, CALIFORNIA, ASSIGNOR TO MANIFOLD IMPRESSIONS CORPORATION, OF CARSON CITY, NEVADA, A CORPORATION OF NEVADA.

RIBBON ATTACHMENT ESPECIALLY ADAPTED FOR TYPEWRITERS.

1,418,624.

Specification of Letters Patent. Patented June 6, 1922.

Application filed September 3, 1921. Serial No. 498,213.

To all whom it may concern:

Be it known that I, MALCOLM L. COSSITT, a citizen of the United States, residing at Alameda, in the county of Alameda and State of California, have invented certain new and useful Improvements in Ribbon Attachments Especially Adapted for Typewriters, of which the following is a specification.

10 My invention relates to means for conveniently attaching a typewriter ribbon, and holding it under proper tension during the period of its use. More especially, my invention is applicable to manifolding ribbons as applied to that type of manifolding attachments for typewriters, in which one or more manifolding ribbons are carried by movable arms and are adapted by the movement of said arms to be thrown into functional position between the sheets of paper, in the line of type-impact, and to be removed therefrom to inoperative position out of the way.

It is in this special relation that, for the sake of illustration, I shall herein disclose my invention, though it is to be understood that I am not to be confined to this use, as the invention may be applicable to any use or in any connection in which a ribbon is to be stretched under tension between carrying members.

In manifolding attachments for typewriters, which comprise a frame adapted to be conveniently secured upon the platen-carriage of the machine, movable arms carried by the frame, and located in the vicinity of the ends of the platen, and one or more single length manifolding ribbons carried by and between said arms, certain essentials are necessary for the successful employment of such ribbons. One is that their connection with the arms shall admit of their ready attachment and detachment, since, in the nature of things, their life is limited. Another is that when applied they shall be under tension, in order that their type impressions may be clear and distinct, and, further, that this necessary tension shall be capable of being restored, if, for any reason, they tend to slacken.

50 Still another essential is that, since their use in the general scheme of the manifolding operation involves their presentation to type-impact along different longitudinal

lines in order that their entire width may be utilized and thus prolong their life, it is necessary that their end connections be such that in whatever line position they may be, the tension shall be uniform throughout their width.

These and other objects are sought to be attained by my invention, and with these ends in view my invention consists in the novel attachment which I shall now fully describe, by reference to the accompanying drawings, in which—

Fig. 1 is a plan view, showing, in a general way, a manifolding device for a typewriter, said device carrying a single ribbon.

Fig. 2 is a section on the line 2—2 of Fig. 1, the dotted lines showing the elevated or non-functional position of the ribbon.

Fig. 3 is a perspective view, showing my ribbon attachment.

Fig. 4 is a face elevation, enlarged, showing the connection between the ribbon-clip and the carrying arm, at one end of the ribbon.

Fig. 5 is an elevation of the inclined end of the carrying arm.

Fig. 6 is a section on the line 6—6 of Fig. 4.

Fig. 7 is a rear elevation, enlarged, showing the connection between the ribbon clip and the carrying arm, at the other end of the ribbon.

Fig. 8 is a section on the line 8—8 of Fig. 7.

Fig. 9 is a perspective view of one of the ribbon clips.

Referring to Fig. 1, the numeral 1 indicates the frame of a typewriter, 2 the keys, 3 the platen carriage, 4 the platen, 5 the spacing ratchet, 6 the main ribbon, 7 the ribbon drums, 8 the spacing lever, 9 the paper guide-apron and 10 the hand-wheels of the platen-shaft.

Secured near each end of the platen carriage is a bracket 11. Extending between and rotatably mounted in these brackets is a rod 12 to which, near each end, is secured an arm 13. Between the free extremities of these arms is carried the manifolding ribbon 14.

It will now be seen by reference to Fig. 2, that by swinging the arms 13 down with the rod 12 as an axis, the manifolding ribbon will be brought down to a position in the line of type impact, and by swinging the

arms up, the ribbon will be carried up to a position above the platen, as seen by the dotted lines.

The typewriter and the manifolding attachment here shown are merely illustrative, it being understood that these may be of varied forms, the only essential being the employment of carrying members and a ribbon stretched between them.

10 My present invention is particularly illustrated in Figs. 3 to 9. From these it will be seen that the free ends 13' of the movable arms 13 are oppositely inclined with respect to each other. In one edge of these 15 ends are made a plurality of tongues 15. To each end of the ribbon 14 is secured a clip 16, the outer portions of the clip being turned back to form a hook, the fold of the hook being on an angle, relatively opposite 20 in the two clips, the angle on each clip corresponding to the angle of the arm end with which it is to be connected. In the fold or crease of each clip hook are made a plurality of holes 17, adapted to receive the locking 25 tongues of the arm ends, when the hook of the clip is slipped upon said end. The clips may be secured to the ribbon in any suitable manner, a good form of connection being to interfold and press them together. The 30 clips are thus permanently attached to, and practically form a unitary part of the ribbon, which is thus in condition to be readily attached to and detached from the arms. The clips have a width about equal to that 35 of the ribbon, but the angular ends of the arms are longer than the width of the clips to afford latitude for selective adjustment.

It will now be seen, as shown in Fig. 3, that if the clipped ribbon has a length sufficient to extend, under proper tension, between the arms when the clips engage the angular arm ends in a given section of said ends, the ribbon, if it subsequently slackens, can have its proper tension readily restored 45 by moving the clips to a different position on said ends. In the angular relation of said ends here shown, this adjustment would be from the extremity towards the base of said ends because the angle of said 50 ends is a converging one; but if the angles should be the other way, the direction of adjustment would be reversed.

It will also be seen that this adjustment can be made as delicate as may be found desirable, both by a predetermined spacing of the locking tongues and holes, and by moving either ribbon clip independently of the other if the adjustment be but slight, though in practice, it will probably be found more 60 desirable for the sake of keeping the ribbon straight, to move both clips uniformly.

The extent of the engagement of the clips with the arm ends being throughout the width of the clips, it follows that as the 65 clips and ribbon have about equal width, the

ribbon is held under firm uniform tension over its entire width. This is of advantage, where, as in practise, different longitudinal portions of the ribbon are presented to the line of type impact.

70 In case a multicolored ribbon be used, the connection herein described being non-reversible, and, therefore, adapting the ribbon for attachment in one way only, no mistake can be made in fitting the ribbon; and, 75 therefore, the different colors will always be in proper place.

I claim:—

1. In a ribbon attachment, adapted for typewriters, an impression ribbon having 80 secured at each end a clip the outer portion of which is angularly folded at relatively opposite angles in the two clips, to form a hook and is perforated in the fold crease.

2. In a ribbon attachment, adapted for 85 typewriters, an impression ribbon having secured at each end a clip the width of which is approximately equal to the width of the ribbon, the outer portion of said clip being angularly folded at relatively opposite 90 angles in the two clips, to form a hook and is plurally perforated throughout the length of the fold crease.

3. A ribbon attachment comprising an impression ribbon; a clip secured at each end 95 of the ribbon, said clip having its outer portion angularly folded at relatively opposite angles, in the two clips, to form a hook, said hook being perforated in the fold crease; and a pair of carrying members the ends of 100 which are oppositely relatively inclined in the two members and are adapted to receive the correspondingly inclined hooks of the ribbon clips, said angular ends of the carrying members being provided with a series of 105 locking tongues to selectively engage the perforations in the clips.

4. A ribbon attachment comprising an impression ribbon; a clip at each end of the ribbon, the width of the clip being approximately equal to the width of the ribbon, said clip having its outer portion angularly folded at relatively opposite angles in the two clips, to form a hook, and said hook being plurally perforated throughout the 115 length of the fold crease; and a pair of carrying members, the ends of which are oppositely relatively inclined in the two members and are adapted to receive the correspondingly inclined hooks of the ribbon clips, said angular ends of the carrying members being provided with a series of locking tongues to selectively engage the perforations in the clips.

5. A ribbon attachment comprising a 125 carrying member having an inclined end; a ribbon; a clip secured to the ribbon end and adapted to engage the inclined end of the carrying member; and means for locking said clip in varying positions along the 130

length of the inclined end of the carrying member.

6. A ribbon attachment comprising a carrying member having an inclined end; a ribbon; a clip secured to the ribbon end and adapted to engage the inclined end of the carrying member; and means for locking said clip in varying positions along the length of the inclined end of the carrying member, consisting of interengaging tongues and holes in said end and clip.

7. A ribbon attachment comprising a carrying member having an inclined end formed with a plurality of tongues; a ribbon; and a clip secured to the ribbon end, formed with an inclined hook adapted to fit upon the inclined end of the carrying member, said hook being perforated in its fold crease to selectively engage the tongues of the inclined end of the carrying member.

8. A ribbon attachment comprising a pair of spaced carrying members with inclined ends, the angle of one end being opposite to that of the other end; a ribbon; a clip secured to each end of the ribbon, each clip having an inclined hook adapted to fit upon the inclined end of the corresponding carrying member; and means for locking said hooked clip in varying positions along the length of the inclined end of the carrying member.

9. In a ribbon attachment adapted for typewriters, an impression ribbon having secured to its end a clip the outer portion of which is angularly folded to form a hook and is perforated in its fold crease.

In testimony whereof I have signed my name to this specification.

MALCOLM L. COSSITT.
